(57) **CLAIM**

The ornamental design for a headwear support assembly, as shown and described.

DESCRIPTION

FIG. 1 is a front perspective view of the headwear support assembly.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a front perspective view of the claimed design shown in a position of use; and,

FIG. 9 is another front perspective view of the claimed design shown in a position of use.

The examples of possible headwear supported by the headwear support assembly shown in broken lines shown in FIGS. 8 and 9 are included for the purpose of illustrating environmental elements only and form no part of the claimed design.

1 Claim, 7 Drawing Sheets
